UNITED STATES PATENT OFFICE.

GEORGE M. HARRIMAN, OF SOUTH THOMASTON, MAINE.

SAW-FRAME.

SPECIFICATION forming part of Letters Patent No. 506,111, dated October 3, 1893.

Application filed March 15, 1893. Serial No. 466,022. (No model.)

To all whom it may concern:

Be it known that I, GEORGE M. HARRIMAN, of South Thomaston, in the county of Knox and State of Maine, have invented a new and 5 Improved Saw-Frame, of which the following is a specification, reference being had to the annexed drawings, forming a part thereof, in which—

Figure 1 is a side elevation of a saw frame 10 provided with my improvement. Fig. 2 is an enlarged sectional side elevation of the pivotal connection of the brace; and Fig. 3 is an end elevation of the same.

Similar letters of reference indicate corresponding parts in all the views.

The object of my invention is to provide a saw frame in which the brace or central part will be pivotally connected with the curved end piece of the saw frame.

20 My invention consists in a saddle adapted to receive the shorter end piece of the saw frame and provided with trunnions, and a socket fitted to the brace or central piece of the frame and provided with a forked end for 25 receiving the trunnions of the saddle, all as will be hereinafter more fully described.

The saw frame is provided with the usual long end piece A, furnished with the handle a, and mortises b, for receiving the forked end 30 of the central bar or brace B; the shorter end piece A', and the straining rod C, the said rod being provided at the center with the usual turn-buckle c. The saw D is received in slots in the end pieces of the saw frame, 35 and held by pins in the usual way. The end of the brace B adjoining the shorter end piece A' of the saw frame is rounded to receive the socket E, provided with the fork d. To the end piece A' is fitted a saddle F, which bears 40 upon the inner edge of the end piece and ex-

tends over the sides thereof, and on opposite sides is provided with trunnions e. The fork d embraces the saddle F, and is provided with notched extremities for receiving the trunnions e. With this construction the end piece 45 A' is provided with a pivotal bearing which allows it to tilt freely in the operation of straining the saw, without injury to the saw frame, and the saddle F may be secured by means of a screw passing through it into the 50 end piece A', or it may be left free to adjust itself along the length of the end piece so that it will come to a natural bearing on the inner edge of the said end piece.

The socket E, with its fork d and saddle F, 55 is preferably made of cast metal, and it may be protected by a coating of japan, or it may be galvanized according to any of the well known methods.

Having thus described my invention, I 60 claim as new and desire to secure by Letters Patent—

1. An attachment for saw frames, formed of a socket adapted to receive the end of the brace of the saw frame, and a saddle fitted to 65 an end piece of the saw frame and provided with trunnions having bearings in the fork of the socket, substantially as specified.

2. The combination, with a saw frame, of the brace B, the socket E, adapted to receive 70 the end of the brace B, and provided with the fork d, and the saddle F, constructed to embrace the end piece A' of the frame, and provided with trunnions e having bearings in the fork d, substantially as specified.

GEORGE M. HARRIMAN.
